US00D838913S

(12) **United States Design Patent** (10) **Patent No.:** **US D838,913 S**
(45) **Date of Patent:** ** *Jan. 22, 2019

(54) **COSMETIC PRODUCT CONTAINER**

(71) Applicant: **EOS PRODUCTS, LLC**, New York, NY (US)

(72) Inventors: **Jonathan Teller**, New York, NY (US); **Sanjiv Mehra**, New York, NY (US); **Peter Waxman**, New York, NY (US); **Joseph Speter**, New York, NY (US); **Sherry Jhawar**, New York, NY (US); **Hamish Campbell**, New York, NY (US)

(73) Assignee: **EOS PRODUCTS, LLC**, New York, NY (US)

(*) Notice: This patent is subject to a terminal disclaimer.

(**) Term: **15 Years**

(21) Appl. No.: **29/574,431**

(22) Filed: **Aug. 15, 2016**

Related U.S. Application Data

(63) Continuation of application No. 29/488,096, filed on Apr. 15, 2014, now Pat. No. Des. 764,711.

(57) **CLAIM**

The ornamental design for a cosmetic product container, as shown and described.

DESCRIPTION

FIG. 1 is a front elevational view of a cosmetic product container showing my design;

FIG. 2 is a left side elevational view thereof;

FIG. 3 is a right side elevational view thereof;

FIG. 4 is a rear elevational view thereof;

FIG. 5 is a top plan view thereof; and,

FIG. 6 is a bottom plan view thereof.

The broken lines in the drawings depict portions of the cosmetic product container that form no part of the claimed design.
